UNITED STATES PATENT OFFICE

147,019

DESIGN FOR A TOY BREAK FRONT OR SIMILAR ARTICLE

Irving Rosenbloom, New York, N. Y.

Application January 9, 1946, Serial No. 125,384

Term of patent 3½ years

(Cl. D34—15)

To all whom it may concern:

Be it known that I, Irving Rosenbloom, a citizen of the United States of America, residing in New York city, county of New York, and State of New York, have invented a new, original, and ornamental Design for a Toy Break Front or Similar Article, of which the following is a specification, reference being had to the accompanying drawing, forming part thereof.

Fig. 1 is a front perspective view of a toy break front or similar article showing my new design.

Fig. 2 is a rear perspective view thereof.

I claim:

The ornamental design for a toy break front or similar article, substantially as shown.

IRVING ROSENBLOOM.
